(57) **CLAIM**

The ornamental design for a sole for shoe, as shown and described.

DESCRIPTION

FIG. 1 is a top perspective view of the sole for shoe;
 FIG. 2 is a top plan view thereof;
 FIG. 3 is a right side view thereof, the left side view being a mirror image of the right side view; and,
 FIG. 4 is a cross-sectional view through the centerline extending in the toe to heel direction along line 4-4 of FIG. 2.
 The broken line structures in the drawings are included for the purposes of illustrating portions of the sole that form no part of the claimed design.
